COMBINED HAIR CURLER AND COMB

Joseph Lloyd Chiariello, Los Angeles, Calif.

Application May 8, 1959, Serial No. 55,843

Term of patent 14 years

(Cl. D86—10)

Fig. 1 is a front elevational view of a combined hair curler and comb showing my new design, the teeth are continuous across the comb and are shown broken away for convenience of illustration;

Fig. 2 is a bottom plan view;

Fig. 3 is a top plan view thereof;

Fig. 4 is a left end elevational view;

Fig. 5 is a right end elevational view;

Fig. 6 is a sectional view on line 6—6 of Fig. 1;

Fig. 7 is a sectional view on line 7—7 of Fig. 1.

I claim:

The ornamental design for a combined hair curler and comb, as shown.
